CLAIM

The ornamental design for a coil component, as shown and described.

DESCRIPTION

FIG. 1 is a front view of the coil component showing our new design.

FIG. 2 is a back view of the design.

FIG. 3 is a left-side view of the design.

FIG. 4 is a right-side view of the design.

FIG. 5 is a plan view of the design.

FIG. 6 is a bottom view of the design.

FIG. 7 is a perspective view of the design.

FIG. 8 is a cross section view of the design taken along line 8-8 shown in FIG. 5; and,

FIG. 9 is a cross section view of the design taken along line 9-9 shown in FIG. 8.

The evenly spaced broken lines depict portions of the coil component that form no part of the claimed design. The dot-dash chain lines depict a boundary of the claimed subject matter and form no part of the claimed design.

1 Claim, 9 Drawing Sheets
